BABY'S CRIB TRAY

Frank E. Rizzuto, Chicago, Ill.

Application May 5, 1950, Serial No. 9,745

Term of patent 14 years

(Cl. D86—10)

To all whom it may concern:

Be it known that I, Frank E. Rizzuto, a citizen of the United States of America, residing at Chicago, in the county of Cook, and State of Illinois, have invented a new, original and ornamental Design for Baby's Crib Tray, of which the following is a specification, reference being had to the accompanying drawings, forming a part hereof.

Fig. 1 is a perspective view showing the front, top and one side of a baby's crib tray embodying my new design;

Fig. 2 is a plan view of the unit shown in Fig. 1; and,

Fig. 3 is a side elevation of the unit shown in Figs. 1 and 2.

I claim:

The ornamental design for a baby's crib tray, as shown.

FRANK E. RIZZUTO.
